UNITED STATES PATENT OFFICE.

FRANK H. GIBSON, OF BRIDGETON, NEW JERSEY.

GLASS-MOLDING MACHINE.

SPECIFICATION forming part of Letters Patent No. 739,666, dated September 22, 1903.

Application filed May 7, 1902, Serial No. 106,302. (No model.)

To all whom it may concern:

Be it known that I, FRANK H. GIBSON, a citizen of the United States, residing at Bridgeton, Cumberland county, New Jersey, have 5 invented certain Improvements in Glass-Molding Machines, of which the following is a specification.

My invention relates to that class of glass-molding presses designed to work continuously for the purpose of making what are known as "glass insulators," such articles having a screw-threaded cavity whereby they may be secured in place.

My invention comprises certain novel features in presses of this character, all of which are clearly shown in the accompanying drawings, in which—

Figure 1 is a side elevation, partly in section, of a press made in accordance with my 20 invention. Fig. 2 is a plan view of the same. Fig. 3 is a sectional view illustrating a detail of my invention. Fig. 4 is a plan view of a structure illustrating a modification of my invention; and Fig. 5 is a sectional elevation 25 of a portion of the structure shown in Fig. 4.

The structure forming the subject of my invention is portable, being mounted upon a suitable wheeled truck, whereby it can be moved to any convenient place in the molding-shop. This portable carriage is provided 30 with a suitable standard which carries the operating mechanism, and near the base of this standard a rotatable table is provided which carries a series of molds.

35 In the accompanying drawings, 1 represents the carriage or truck supporting the mechanism employed in operating the molds 2.

3 is a standard mounted upon said truck, preferably at the center of the same.

40 4 represents the base portion of the standard, and 5 the rotatable table mounted upon said base and having an interposed ball-bearing 6, said table serving to support the molds 2, within which the glass insulators are formed,

45 and also the annular frame 7, carrying the screw-plungers 8, whereby the threaded interior of the insulator is formed. These screw-plungers are provided with handles 9. The annular frame 7 is supported by means 50 of brackets 10, secured at their opposite ends

to the inside of the same, said brackets having projecting feet, which are bolted to the table 5.

Carried by the standard 3 and secured thereto by means of set-screws 11 is a sleeve 12, which supports a plunger 13 and the mechanism for operating the same. The plunger 13 is guided in a boss 14, carried by an arm 15, projecting from the sleeve 12, and pivoted to this boss 14 at 16 is a lever 17.

Pivotedly mounted at 18 on the arm 15 of the sleeve 12 is a link 19, which is connected to the lever 17 by means of a link 20. The plunger 13 carries an adjustable collar 21 near the upper end of the same, and to bring this 65 plunger into operative connection with the lever or handle 17 a connecting-rod 22 is employed, which is pivoted to said collar at 23 and to the link 19 at 24. By pulling down on the lever 17 the plunger 13 will be depressed, and when said plunger is directly over one of the screw-plungers 8 and the latter is in line with the central opening of the mold said screw-plunger will be forced into the molten glass contained within said mold. 75

The molds 2 are similar in all essential respects to molds heretofore used in the manufacture of articles of this class. In the present instance they are provided with tops or follower-plates 25, having handles 26, where- 80 by said plates or followers may be readily laid on said molds or removed therefrom.

In order that the stops or follower-plates of the molds may be maintained in a fixed position during this forcing of the screw-plunger 85 into the molten glass contained therein, I provide the steadyng-roads 27. These rods are carried by an adjustable collar 28, mounted on the plunger 13, passing through bosses 29 on the same. At the lower end these rods are 90 guided by passing through bosses 30, carried by a collar 31, secured to the lower end of the plunger 13.

Interposed between the bosses 29 of the upper collar 28 and adjustable collars 32, carried by the rods 27, are the springs 33. When the plunger 13 is depressed, as before indicated, the rods 27 will be carried down into contact with the tops or follower-plates of the molds and will be stopped thereby, the 100

further movement of the plunger 13 compressing the springs 33 and imparting the necessary holding effect of the rods 27.

As noted, the screw-plungers may be readily 5 pushed into the molten glass contained within the mold by the pressure exerted by the plunger 13; but in order that the thread which is formed by the introduction of such screw-plungers into the glass may be preserved it is 10 necessary that they be screwed out, and I accomplish this result in the following manner:

The annular ring 7, supporting the screw-plungers 8, is provided with a series of detachable members 35, which carry the screw-plungers 8, which members have openings 36, through which said plungers are adapted to pass. These openings 36 are smooth, so that unless holding means be provided the screw-plungers may freely slide up and down 20 through the same. In order, however, to hold these screw-plungers in place and to provide means whereby they may be raised out of the mold by the simple turning of the same and, further, to insure that said plungers may be 25 readily depressed and forced into the glass, I provide each member 35 with a spring-controlled pin 37, (clearly shown in Fig. 3,) which pin engages the threads of said screw-plunger. This pin is arranged in a boss 38 at the side 30 of the members 35 and is held in place by means of the screw-cap 39, through the center of which said pin projects. Interposed between said screw-cap and the head of the pin is a spring 40. It will be readily understood, therefore, that while the spring-controlled pin is sufficient to support the screw-plunger and will also engage the thread of the same and act as a nut when it is desired to raise the screw-plunger by turning the 40 same it will not prevent the ready depression of said screw-plungers when acted upon by the plunger 13. The screw-plungers have threads interrupted at the point 41, which portion is adjacent to the aperture in the follower-plate when the screw-plungers are 45 forced into place in the molds.

In order to center the molds and screw-plungers carried by the table beneath the plunger 13, the table is provided with notches 50 or nicks 42 on the under side in line with the centers of the molds and screw-plungers, and adapted to engage these notches or nicks is a spring-controlled holding-pawl 45. The table is readily rotatable by hand, and after 55 the molds have been filled with glass they are then brought beneath the plunger 13, by which the screw-plungers will be forced into the glass. After this the table will be given a partial rotation to bring the next screw-plunger and mold beneath the plunger 13, and so on throughout the operation of the machine. When the glass in the mold has 60 sufficiently cooled, each screw-plunger 8 may be rotated by means of its handles and will

be thereby lifted from the mold. After this 65 has been done the molds may be emptied and fresh molds put in their place.

In practice it often occurs in machines of this character that the heating of the screw-plungers takes place very rapidly and it becomes impossible to operate the same by hand. In order to prevent as much as possible this heating of the handles 9 and keep the plungers sufficiently cool to prevent the glass sticking to the same, I may provide a modified 75 structure, such as illustrated in Figs. 4 and 5, in which 50 represents a wheel-like structure carried by the standard 2 and having a series of screw-plunger carriers 35^a mounted on the rim 51. These plunger-carrying members are provided with threaded bolts 52 and washers 53, which secure the rollers 54 in place above and below the rim 51. The wheel is fixed to the standard 3^a preferably by a spline or key 55, and all of the plunger-carrying members 35^a are movable around the rim. Hence a greater number of plungers can be used, as they can be kept sufficiently cool to screw out of the glass readily. These plunger-carrying members 35^a are set equidistant 80 throughout the rim and are spaced apart by the adjusting-nuts 56. As shown in the accompanying drawings, these members 35^a are readily detachable by simply removing one set of rollers and their securing means. I 85 may provide, however, a hinged-rim segment, whereby the screw-plunger carrying members may be readily placed upon or removed from the rim 51. In each instance these screw-plunger carriers carry the spring-controlled 90 pins 37 to engage the threads of the plunger.

Having thus described my invention, I claim and desire to secure by Letters Patent—

1. In a glass-molding machine, the combination of the table, a mold carried thereby, an independent screw-plunger, a guiding-holder for the same, a yielding member carried by the holder and engaging said screw-plunger, a pressure-plunger, a support for the same, and means for depressing the latter plunger whereby it may engage the screw-plunger, substantially as described.

2. The combination in a glass-molding machine, of a table, a series of molds carried thereby, a series of independent screw-plungers arranged to be forced into the glass charged in said molds, guiding-holders for said screw-plungers, yielding members mounted in said holders and engaging said screw-plungers, said members permitting the depression of the plungers in a vertical line, a pressure-plunger arranged to engage the screw-plungers, a support for said pressure-plunger, and means for actuating the latter, substantially as described.

3. The combination in a glass-molding machine, of a rotatable table, a series of molds

carried thereby, a series of plungers having threaded ends and threaded spindles, the threaded ends adapted to be forced into the glass charged in said molds, guiding-supports 5 for said plungers, yielding means carried by said supports and engaging the threaded spindle of said plungers, such yielding means acting as a retaining device while permitting the depression of the screw-plungers, a pressure-plunger arranged to engage the screw-plungers, and means for actuating said pressure-plunger, substantially as described.

4. In a machine for molding internally-threaded glass insulators, a rotary table having a series of molds seated thereon, a plunger and a threaded spindle with unscrewing means situated over each mold with means to yieldingly support them, combined with a single depressing mechanism having a fixed 15 position under which the molds with the threaded spindles and attachments as described are successively brought and whereby, in its actuation one of the threaded spin-

dles is plunged into the mold directly below the same.

5. In a machine for molding internally-threaded glass insulators, a rotary table having a series of molds seated thereon, follower-plates for said molds, a plunger and a threaded spindle with unscrewing means situated 20 over each mold, with means to yieldingly support them, combined with a single depressing mechanism having a fixed position, under which the molds with the threaded spindles and attachments as described are successively brought and whereby, in its actuation, a mold covered by its follower-plate has a threaded spindle plunged therein.

In testimony whereof I have signed my name to this specification in the presence of 25 two subscribing witnesses.

FRANK H. GIBSON.
